UNITED STATES PATENT OFFICE.

ROBERT L. POE, OF CHICAGO, ILLINOIS, ASSIGNOR TO ARDELLA C. DILBONE, OF COOK COUNTY, ILLINOIS.

COOKING RANGE.

1,407,768.

Specification of Letters Patent. Patented Feb. 28, 1922.

Application filed April 21, 1919. Serial No. 291,668.

To all whom it may concern:

Be it known that I, ROBERT L. POE, a citizen of the United States, residing at Chicago, in the county of Cook and State of Illinois, have invented certain new and useful Improvements in Cooking Ranges, of which the following is a specification.

This invention relates to improvements in cooking ranges, and has for its object to provide a new and improved form of range, of the type shown in my copending application Serial No. 98,582, filed June 15, 1916.

The object of my invention is to provide a range containing one or more ovens spaced from the surrounding casing so as to provide circulation spaces for the passage of the heated gases around the oven or ovens, and to provide passages for air, which is delivered to the fire-box commingled with the flame and products of combustion to enhance the combustion, these passages being so arranged as to preheat such air prior to its delivery at the combustion point.

These and other objects of the invention will be more fully set forth and described in the following specification and shown in the accompanying drawings, in which—

Figure 1 is a vertical longitudinal section taken along the line 1—1 of Fig. 2; and Fig. 2 is a horizontal section taken along the line 2—2 of Fig. 1.

Like numerals refer to like elements throughout the drawings, in which—

10 designates, generally, a casing provided with a top 10^a, ends 10^b, bottom 10^c, and front 10^d. Located in the casing are the ovens 11 and 12 extending from front to back and spaced at their sides, top, and bottom from each other and from the casing to provide circulation spaces for the heating gases. Located at one end of the casing is the fire-box 13 and ash pit 14, a grate 15 separating these two elements. The fire-box is provided with inner walls 13^a, 13^b, spaced from the side wall of the oven 12 and end wall 10^b of the casing, as shown in Fig. 2, thereby forming air passages or chambers 16 and 17 closed at the top by portions 13^c and 13^d, respectively, save for apertures 20, as shown in Figs. 1 and 2. The ash-pit is similarly provided with walls 14^a, 14^b coplanar with the inner walls 13^a and 13^b, respectively, of the fire-box, thereby forming continuations of the air chambers or passages 16 and 17, as shown in Fig. 1.

Extending along the bottom of the casing is the air duct 25, provided with an inlet 25^a at the left-hand end of the range, as shown in Fig. 1. Apertures 26 provide communication between this passage or duct and the chambers 16 and 17—see Figs. 1 and 2.

It will be apparent that in the functioning of my structure, assuming fire to be burning in the fire-box 13, air will be drawn through the port 25^a, through the passage 25 in the direction of the arrows, and will flow upwardly through the chambers 16 and 17, and outwardly through the apertures 20 across the flame in the fire-box. I have found that by supplying pre-heated air in this manner the efficiency of the combustion in the fire-box is so greatly enhanced as to approach perfection, and the consumption of coal is reduced to an unbelievable minimum. It will be apparent that the air flowing through the passage 25 will be pre-heated, owing to its proximity to the current of heat gases flowing beneath the bottom of the ovens, and will at the same time serve as an insulating medium to protect the floor from the heat of the range, thereby overcoming the objections to present-day ranges, which so often cause fires. This pre-heating is increased during the flow of this combustion-enhanced air upwardly through the chambers 16 and 17, especially where they lie on each side of the fire-box, so that this air is heated to a very considerable degree at the time it flows through the apertures.

An exhaust pipe 30 is provided at the back of the range, and a baffle plate 31 extends partially beneath the oven 12 to ensure maximum circulation of the flow of heating gas beneath said oven. To increase the draft when stirring the fire, I provide a damper 32 controlled by a rod 33 and lever 34—see Fig. 1. When this damper is open in starting a fire, a short course is provided for the products of combustion, the circulation around the ovens being eliminated until the fire has reached the proper stage, when the dampers may be shut.

It will be apparent that my invention is susceptible of modification and improvement, and I do not, therefore, wish to be restricted to the form shown, save as defined in the appended claim.

I claim:—

In combination, a range comprising a casing, an oven therein, a fire box, air chambers

adjacent said fire box, one on each side thereof, and an air-heating passage extending along the bottom of said range substantially from end to end of said casing and provided 5 with an inlet at one end communicating with the atmosphere exterior of said casing and beneath the latter, and a plurality of outlets

at the other end of said passage, one for each of said chambers, the latter being provided with openings leading into said fire box 10 above the normal level of the fuel therein.

In testimony whereof, I have subscribed my name.

ROBERT L. POE.
